TAPE RECORDER

Frank T. Walsh, Pasadena, Calif., assignor to Consolidated Electrodynamics Corporation, Pasadena, Calif., a corporation of California

Application December 5, 1955, Serial No. 39,155

Term of patent 14 years

(Cl. D26—14)

FIG. 1.

FIG. 2.

FIG. 3.

FIG. 4.

FIG. 5.

Fig. 1 is a front perspective view of a tape recorder showing my new design;

Fig. 2 is a front elevational view of the recorder of Fig. 1;

Fig. 3 is a rear elevational view of the recorder of Fig. 1;

Fig. 4 is a right end elevational view of the recorder of Fig. 1; and

Fig. 5 is a left end elevational view of the recorder of Fig. 1.

The dominant features of my design reside in the portions shown in full lines.

I claim:

The ornamental design for a tape recorder, as shown and described.
